TABLE FOUNTAIN

Ernest R. Johnson, 2023 Mulford St.,
Camden, N.J. 08104

Filed May 31, 1966, Ser. No. 2,460

Term of patent 7 years

Int. Cl. D23—01

U.S. Cl. D23—13

FIG. 1.

FIG. 2.

FIG. 3.

FIG. 4.

FIG. 5.

FIG. 6.

FIG. 1 is a top view of a table fountain showing my new design.

FIG. 2 is a front view thereof.

FIG. 3 is a side view thereof; the opposite side being a mirror image.

FIG. 4 is a cross-sectional view thereof, taken on the line 4—4 of FIG. 1;

FIG. 5 is a cross-sectional view thereof, taken on the line 5—5 of FIG. 1; and

FIG. 6 is a bottom view thereof.

I claim:

The ornamental design for a table fountain, as shown and described.
